UNITED STATES PATENT OFFICE.

JULIUS PROEGER, OF GREENSBURG, PENNSYLVANIA.

DESIGN FOR A BOTTLE.

SPECIFICATION forming part of Design No. 24,695, dated September 24, 1895.

Application filed July 28, 1893. Serial No. 481,775. Term of patent 3½ years.

To all whom it may concern:

Be it known that I, JULIUS PROEGER, of Greensburg, in the county of Westmoreland and State of Pennsylvania, have invented a new and original Design for Glassware, of which the following is a full, clear, and exact description, reference being had to the accompanying drawings, in which—

Figure 1 is a side elevation, and Fig. 2 is a cross-section of a bottle provided with my improved design.

My invention relates to a design for bottles and similar articles; and it consists in such an article having upon its side an inclosed space which is crossed by a curved rib, the portion on one side of the rib being concave and that on the opposite side being convex.

In the drawings, 2 represents a bottle having an inclosed space in the form of an ellipse bounded by the line 3, 4 being the reversely-curved rib, 5 the concave portion, and 6 the convex portion. 20

I claim—

The design for bottles and similar articles substantially as herein shown and described. 25

In testimony whereof I have hereunto set my hand.

JULIUS PROEGER.
